UNITED STATES PATENT OFFICE

LEWIS T. HOUGHTON, OF WORCESTER, MASSACHUSETTS; JOHN M. HOUGHTON AND OLIVE M. LAMBERT, EXECUTORS OF SAID LEWIS T. HOUGHTON, DECEASED, ASSIGNEES TO JOHN M. HOUGHTON AND OLIVE M. LAMBERT, BOTH OF WORCESTER, MASSACHUSETTS

ATTACHMENT FOR SPOOLER GUIDE RODS

Application filed April 27, 1928. Serial No. 273,400.

This invention relates to the guide rods employed in spoolers over which the yarn passes.

The principal object of the invention is to provide a very simple and convenient means for providing a smooth surface over which the yarn passes after the original surface has been cut or scored by the yarn.

Other objects and advantages of the invention will appear hereinafter.

Reference is to be had to the accompanying drawings, in which

Fig. 1 is a perspective view showing an ordinary spooler guide rod and indicating the scoring and roughening it gets in wear due to the yarn passing over it;

Fig. 2 is a similar view showing the application of my invention thereto; and

Fig. 3 is a perspective view of the attachment which constitutes this invention.

As is well known, spoolers are provided with a guide rod 10, over which the yarn passes from below in a horizontal direction. These rods are made of ordinary stock, and after the yarn has passed over it in one place after a time it will become scored. Such grooves 11 in it are indicated in Fig. 1.

The ordinary way of restoring the rod to proper condition for use is to turn it about its axis. This requires the loosening of the clamps 12 which hold the guides 13 in position, and the readjustment of the guides through which the yarn passes from it. Furthermore, this has to be done when any one of the guiding surfaces of the long rod becomes badly worn, although the others may not have been worn to the same extent.

In order to overcome these difficulties in a very simple way, I provide a semi-cylindrical steel clip 15 which is made of sheet steel stock and highly finished and polished on its convex surface, and which extends around slightly more than a semi-circle, so that it can be pressed on from above into the position shown in Fig. 2 and will remain there by the action of the natural resiliency of the clip itself. No further fastening means has to be employed, and no appreciable amount of time has to be taken up in applying it. The clamps 12 do not have to be loosened, and

the guides 13 do not have to be readjusted. These clips can be placed in any position along the rod that may be desired without interfering with the rod in any places where it is not badly worn.

After it is placed in position the clip can be turned on the rod at least once and usually to three different positions without removing it and without taking it off so as to present different surfaces to the yarn. Furthermore, being formed of steel it is a very simple matter to finish its surface very smooth, so that when placed in position it constitutes a better surface than that of the original rod. Also, on account of the material of which it is made, it will wear longer than the original rod in one place.

It is very inexpensive to manufacture and does not add materially to the cost of the equipment, but the principal saving may be said to be in the time required to turn an ordinary rod and readjust the associated parts. This also increases the life of the original rod, because it can be turned in the usual way several times, and these clips applied only after the rod is really used up. It constitutes a very inexpensive means for practically replacing the original rod.

Furthermore, on account of the slowness of the wear on this steel clip, the product is less likely to be damaged by the grooves worn in it, or at least the time during which the surface is perfectly smooth is very materially increased.

Although I have illustrated and described only a single form of the invention, I am aware of the fact that modifications can be made therein by any person skilled in the art without departing from the scope of the invention as expressed in the claims. Therefore, I do not wish to be limited to the exact form shown, but what I do claim is:

1. As an article of manufacture, a clip for application to a spooler guide rod, consisting of a short length of sheet steel formed in a convex shape on the outside and of the same size as the rod inside, and of a width slightly more than half the circumference of the cylinder and adapted to be clipped on the rod and held thereon by its own resiliency.

2. As an article of manufacture, a clip for the purpose described, consisting of a piece of sheet steel of a length sufficient to receive the yarn passing to a single guide on the pooler, and of a concave shape inside, adapted to clip over the spooler guide rod to hold it thereon by its own resiliency, and having a smoothly finished convex surface for receiving the yarn.
- 10 3. As an article of manufacture, a clip for application to a spooler guide rod, consisting of a length of sheet steel of the same size as the rod inside and more than semi-cylindrical in cross section, and adapted to be pressed on the rod and to be held thereon by its own resiliency, and to be turned thereon without removing it to present a fresh wearing surface.

In testimony whereof I have hereunto affixed my signature.

LEWIS T. HOUGHTON.
